Fig. 2.

Fig. 3.

*Fig. 4.**Fig. 5.*To all whom it may concern:

Be it known that we, Ernest J. Svenson and Joseph W. Phillips, citizens of the United States, and residents of Rockford, Winnebago County, State of Illinois, have invented a new, original, and ornamental Design for Power Steering Tester, of which the following is a specification, reference being had to the accompanying drawings, forming a part thereof.

Fig. 1 is a front elevational view of a power steering tester showing our new design;

Fig. 2 is a top plan view thereof;

Fig. 3 is a side elevational view taken from the right of Fig. 1;

Fig. 4 is a side view taken from the left of Fig. 1; and

Fig. 5 is a rear elevational view.

We claim:

The ornamental design for a power steering tester, as shown.
